UNITED STATES PATENT OFFICE.

JOSE CASTILLO PERAZA, OF NEW YORK, N. Y.

VALVE MECHANISM FOR INTERNAL-COMBUSTION ENGINES.

Application filed March 24, 1921. Serial No. 455,307.

To all whom it may concern:

Be it known that I, JOSE CASTILLO PERAZA, a citizen of the Republic of Mexico, residing at and whose post-office address is 285

5 St. Nicholas Avenue, in the city of New York, county and State of New York, have invented certain new and useful Improvements in Valve Mechanism for Internal-Combustion Engines; and I do hereby 10 declare the following to be a full, clear, and exact description of the invention, such as will enable others skilled in the art to which it appertains to make and use the same.

The invention relates to valve mechanism 15 for internal combustion engines and has for its object to provide a simple and efficient arrangement of combined rotary and poppet valve for controlling the inlet and exhaust of the engine and to practically eliminate 20 possibility of leakage past the valves during the compression and explosion strokes of the engine. The invention is applicable to either single cylinder or multi-cylinder engines, and in either event it is designed to 25 materially reduce the number of parts and simplify the construction of the valve mechanism, and, in the case of a multi-cylinder engine, to provide a highly simplified construction of valve mechanism that may 30 be quickly assembled and applied to the engine without the necessity of delicate and careful adjustment of the valves and cams, required in the ordinary types of valve mechanism.

35 The invention is illustrated in the accompanying drawings, in which:—

Fig. 1 is a vertical longitudinal section of the upper portion of a four cylinder internal combustion engine having the improved valve mechanism applied thereto;

Fig. 2 is a vertical section on line 2—2 of Fig. 1;

Fig. 3 is a corresponding section on line 3—3 of Fig. 1;

Fig. 4 is a perspective view of the shaft which carries the rotary valves and the cams for operating the poppet valves;

Fig. 5 is a perspective view of one of the cams;

Fig. 6 is a perspective view of one of the rotary valves; and

Fig. 7 is a diagrammatic view of the various rotary valves shown in Fig. 1.

Referring to Fig. 1 of the drawings, 1 55 indicates the main casting of the engine, containing the cylinders I, II, III and IV,

in which the usual pistons reciprocate. Secured to the top of the cylinder casting is a casting 2, which serves as a housing for the valve mechanism and also contains the passages leading from the respective cylinders to the inlet and exhaust connections. Secured to the top of the casting 2 is a third casting 3, which forms the top part of the housing for the rotary valves and also contains a longitudinal inlet passage or manifold 30 and an exhaust passage or manifold 31, parallel and adjacent thereto, and separated from the inlet manifold by a relatively thin partition, so that the contents of the inlet manifold will be heated to a relatively high temperature by the exhaust gases traversing the exhaust manifold. It will be understood that the three unitary castings are connected together by the usual form of gas-tight joints employed in mechanism of this character. Supported in the ends of the castings 2 and 3 are suitable journal bearings 20 and 21, in which is operatively supported a shaft 6 provided with journals 7 and 10 near its ends, which engage the bearings 20 and 21 respectively, a collar 8 near one end of the shaft serving to take up the longitudinal thrust on the shaft. The main body of the shaft is substantially square in cross section and is provided at spaced intervals with transverse openings 14 disposed successively at angles of 90°, so that when the first and third of the openings 14 are vertical, the second and fourth will be horizontal. This particular angular disposition of the slots or openings, however, is purely arbitrary and applies only to the specific sequence of operation of the cylinders, as illustrated in Fig. 1. It will be understood that if any other order or sequence of operation is desired, the arrangement of the slots or openings 14 will be correspondingly modified.

Mounted longitudinally on the shaft 6 are four valve bodies 15 which are substantially cylindrical in shape and fit closely within the circular bore 4 formed between the castings 2 and 3, each of said valve bodies being provided with a longitudinal central opening 16 accurately fitting the shaft 6, and a transverse port 17 conforming to and adapted to be brought into registry with a corresponding slot or opening 14 in the shaft. Mounted on the shaft and interposed between the valve bodies 15 is a series of double cams 18, preferably of the shape shown in Figs. 2 and 5, the central hub por-

tion of which is pierced with a square opening to fit the shaft 6. These cams are each designed to operate a reciprocating or poppet valve in proper timed relation to the 5 operation of the corresponding rotary valve 15. In the particular disposition of the apparatus shown, the several double cams 18 will be arranged with their longitudinal axes successively at right angles, the longitudinal axis of each cam being substantially 10 parallel with the longitudinal axis of the port or passage 17 of the adjacent rotary valve. When the rotary valves 15 and the cams 18 are assembled on the shaft, they are 15 locked against longitudinal movement thereon by a suitable set nut 9' engaging the screw threaded shoulder 9 on the shaft, adjacent the journal 10.

Properly timed rotary motion is imparted 20 to the shaft 6 by means of a gear 22 splined to the reduced end 7 of the shaft and locked thereon by means of a nut engaging the extreme outer threaded end 12 of said shaft, said gear 22 being driven by a bevelled 25 pinion 23 on a shaft 24, which latter is preferably driven from the crank shaft of the engine.

The casting 3 is provided with inlet ports 32 and exhaust ports 33, communicating 30 with the inlet manifold 30 and the exhaust manifold 31, opposite each of the rotary valves 15 and adapted to be brought successively into communication with the passage or port 17 in the corresponding rotary valve.

The casting 2 is provided with ports 34 and 35 adjacent each rotary valve 15, which establish communication between the casing of the rotary valve and the corresponding cylinder by means of a passage 36, of the form 35 shown in Figs. 1, 2 and 3, so that, when the port 17 in a given rotary valve registers with the inlet port 32, communication will be established between the corresponding cylinder and the inlet manifold, and when 40 the passage 17 and the rotary valve register with the port 35, the corresponding cylinder will be opened up to the exhaust.

The lower end of each of the passages 36 terminates in a valve seat 37, which is 50 centrally disposed with respect to the bore of the corresponding cylinder, and cooperates with a poppet valve 40 carried by a stem 41, slidably mounted in a guideway formed in the casting 2 and carrying on its upper end 55 a head 43, in which is mounted a bowl or roller 44, which cooperates with the corresponding cam 18. A helical spring 42 surrounding the stem and confined by the head 43 and the bottom of the recess in the casting 60 serves to normally seat the valve 40. It will be particularly noted that the actuating cam for each of the valves 40 is in vertical alignment with the stem of the corresponding valve, so that the valve is actuated directly 65 and positively by its cam and without the in-

terposition of rock levers or other connecting elements.

In the normal operation of the apparatus, as described, the inlet manifold 30, which is in direct communication with the carburetor, or other source of supply of explosive mixture, is heated by the products of combustion passing through the exhaust manifold, which has the effect of accelerating the gasification of the fuel and raising 75 the temperature of the mixture before the same enters the cylinder or cylinders of the engine. Each cylinder takes up the normal operation of a four-cycle engine in turn, and both the rotary valve 15 and the poppet 80 valve 40 of each cylinder are operated at the proper times to effect the normal functioning of a four-cycle engine. For example, assuming cylinder I to be at the beginning of the explosion cycle, the corresponding rotary valve 15 and poppet valve 85 40 are both closed. Cylinder No. II is in the initial exhaust stage, poppet valve 40 being opened by the cam 18 and rotary valve 15 being moved to position so that its port 90 17 establishes communication between the ports 35 and 33, which permits the products of combustion to pass by way of the passage 36 directly into the exhaust manifold 31. Cylinder No. III is in the compression stage, 95 and both valves 15 and 40 are closed. Cylinder No. IV is in the beginning of the suction cycle and valve 40 is held open by a cam 18 and the port of the rotary valve 17 has been turned to connect ports 32 and 34 100 105 which opens up the cylinder to the explosive charge, which enters by way of manifold 30, port 32, valve passage or port 17, port 34, passage 36, and past open valve 40 into the cylinder.

Inasmuch as valves 15 and 40 are always closed at the same time, it will be apparent that it will not be necessary to provide any special packing means for the rotary valve, although, under certain circumstances it may 110 be desirable to provide ordinary packing to prevent possible leakage. It will be understood that the poppet valve 40 in each cylinder constitutes the first check to the loss of compression or of pressure, and should it 115 happen that one or more of the poppet valves proves leaky, the loss would be checked by the corresponding rotary valve, which effectively closes the passage 36.

It will be particularly noted that the construction and arrangement of the valve mechanism is exceedingly simple, involves few parts and is of such character that it may be applied and adjusted by ordinary unskilled labor with the assurance that the 120 several parts will be in proper cooperative relation. By merely removing the top casting 3 access is had to the entire series of rotary valves and actuating cams for adjustment and repair, and, if it is found necessary 125 130

to replace any or all of these elements, a new set may be assembled on the shaft 6 by sliding the valves and cams on alternately, it being necessary only to observe that the 5 ports or passages 17 in the several rotary valves are in alignment with the corresponding openings 14 in the shaft, and that the cam 18 corresponding to a given rotary valve is in proper position to open and close 10 the co-operating poppet valve in consonance with the opening and closing of the associated rotary valve.

What I claim is:

1. An internal combustion engine comprising a cylinder having a port therein, a poppet valve coacting with said port, inlet and exhaust passages above said port, a rotary valve interposed between said port and passages adapted to establish communication 15 between the cylinder and the inlet and exhaust passages alternately, and a cam on the axis of said valve directly engaging the stem of said poppet valve to open the latter concurrently with the opening of the inlet 20 and exhaust passages by said rotary valve.
2. An internal combustion engine comprising a cylinder, a head therefor having a ported passage therein, a poppet valve coacting with the port, a rotary valve in said 25 head, inlet and exhaust passages in said head above the rotary valve adapted to be connected successively by said rotary valve with the ported passage aforesaid, and a cam on the axis of said rotary valve directly engaging 30 the stem of said poppet valve to open the latter concurrently with the opening of the inlet and exhaust passages by said rotary valve.
3. An internal combustion engine comprising a cylinder, a head having a ported passage communicating with the cylinder, inlet and exhaust passages above said ported passage, a rotary valve having a single passage adapted to connect the ported passage with 35 the inlet and exhaust passages alternately, a poppet valve cooperating with said ported passage to open and close the same, and a cam on the axis of said rotary valve directly 40 engaging the stem of said poppet valve to open the latter concurrently with the opening of the inlet and exhaust passages by said rotary valve.
4. An internal combustion engine comprising a cylinder, a head having a ported passage communicating with the cylinder, a rotary valve casing communicating with said 45

ported passage, a rotary valve having a through passage in said casing, inlet and exhaust passages above and connected with said ported passage through the passage of 50 the rotary valve, a poppet valve mounted in said head coacting with the ported passage aforesaid, and a cam on the axis of said rotary valve directly engaging the stem of 55 said poppet valve to open the latter concurrently with the opening of the inlet and exhaust passages by said rotary valve.

5. A multiple cylinder internal combustion engine comprising a head having adjacent longitudinal supply and exhaust passages 60 therein, a cylindrical valve chamber adjacent said passages and having ports connecting therewith, a shaft journalled longitudinally of said chamber, rotary valves for the respective cylinders mounted on said 65 shaft, combined inlet and exhaust passages connecting the cylindrical valve chamber with the several cylinders, poppet valves controlling the connections of said combined passages with the cylinders, and cams 70 on said shaft adjacent the rotary valves directly engaging the stems of the poppet valves to open the latter when the corresponding rotary valves open the corresponding inlet and exhaust ports.

6. An internal combustion engine comprising multiple cylinders, a head having inlet and exhaust passages and an adjacent longitudinal cylindrical bore therein, a shaft journalled in said bore having a square intermediate section provided with transverse 75 passages, cylindrical valves mounted on said shaft having through ports registering with the passages in said shaft, cams on said shaft adjacent said valves, a combined inlet 80 and exhaust passage for each cylinder connecting with said longitudinal cylindrical bore, and a poppet valve cooperating with each combined passage and actuated by the corresponding cam.

7. A valve construction for internal combustion engines comprising a shaft having a square intermediate section provided with transverse passages, cylindrical valves each having a square opening engaging the square 85 shaft section and a transverse through port registering with a transverse passage in said shaft, and means for locking the valves in proper relation on the shaft.

In testimony whereof I affix my signature.

JOSE CASTILLO PERAZA.
